UNITED STATES PATENT OFFICE.

RUEL W. WHITNEY AND ABNER C. STOCKIN, OF SOUTH BERWICK, MAINE.

IMPROVED MOP-HEAD.

Specification forming part of Letters Patent No. **58,703**, dated October 9, 1866.

To all whom it may concern:

Be it known that we, RUEL W. WHITNEY and ABNER C. STOCKIN, of South Berwick, in the county of York and State of Maine, have invented an Improved Mop-Head, and do hereby declare the same to be fully described in the following specification and represented in the accompanying drawings, of which—

Figure 1 is a side view of a mop with our improvement; Fig. 2, a longitudinal section, and Fig. 3 a transverse section, of it.

In such drawings, A denotes the mop-handle as projecting from the middle of a bearer, B, and at right angles with such.

A yoke or clasp, C, which encompasses the bearer and is formed in manner as represented, goes through the handle A, so as to be capable of being turned laterally from its position when directly over and encompassing the bearer, as shown in the drawings.

A ring or collar, d, is so adapted to the handle and the two arms e e of the yoke as to be capable of being slid on and off such arms. When on the arms it will prevent the yoke from being turned off the bearer.

The mop-cloth f is placed within the yoke, and by it is held against the bearer, in manner as shown in the drawings.

We are aware of the mop-head described in Letters Patent No. 17,877, granted to James Harris, and therefore do not claim such, it being composed of two wire jaws applied to a

handle, and operating with a roller wholly disconnected from the handle, such roller when in use being simply introduced into the mop-cloth.

This mop-head not only differs from our mop-head in construction, but holds the cloth in a manner very different from that in which it is held by the latter. In our mop-head the cloth, instead of being first bent around a roller or pin and grasped by and between jaws, as it is in the mop-head of the said Harris, is simply bent around a part of the yoke, and is held in place thereon by being drawn by the yoke against one edge of the bearer. Besides, in Harris's mop-head there is nothing which operates like, or is the equivalent for, the bearer B of our mop-head, such bearer being permanently fixed to the end of the handle. This bearer enables us to use but one jaw or yoke, such as is employed by Harris. With our invention the bearer is a fixture not liable to be lost.

We claim as our invention—

The improved mop-head made as described—viz., of the bearer, the yoke, and the collar, constructed, arranged, and applied together and to the handle substantially as specified.

RUEL W. WHITNEY.
ABNER C. STOCKIN.
